Des. 201,252
Patented June 1, 1965

201,252

AERIAL TOP

Stephen J. Salayka, 103 Berry St., Brooklyn, N.Y.

Filed Dec. 10, 1964, Ser. No. 83,118

Term of patent 14 years

(Cl. D34—15)

FIG 4

FIG 5

FIG. 1 is a view in elevation from a first side of the aerial top showing my new design;

FIG. 2 is a view in elevation from the other, second side of the aerial top;

FIG. 3 is a view in plan of the aerial top;

FIG. 4 is a view in perspective of the aerial top, the view being taken from a position offset from the axis toward the second side of the aerial top, the operating string for the top being omitted for convenience of illustration; and

FIG. 5 is a view in plan of the aerial top similar to FIG. 3 but with parts of the upper portion of the body of the top, the spinner member of the top, and the spinner retaining means in axial section.

This application is a continuation-in-part of design patent application Ser. No. 79,039, filed March 17, 1964.

I claim:

The ornamental design for an aerial top, as shown and described.
